S. H. CAMPBELL

COUPLER RELEASE RIGGING

Filed June 22, 1923

Patented Sept. 16, 1924.

1,508,380

UNITED STATES PATENT OFFICE.

STERLING H. CAMPBELL, OF ST. LOUIS, MISSOURI.

COUPLER-RELEASE RIGGING.

Application filed June 22, 1923. Serial No. 646,994.

To all whom it may concern:

Be it known that I, STERLING H. CAMPBELL, a citizen of the United States of America, residing at the city of St. Louis, State of Missouri, United States of America, have invented a certain new and useful Coupler-Release Rigging, of which the following is such a full, clear, and exact description as will enable anyone skilled in the art to which it appertains to make and use the same, reference being had to the accompanying drawings, forming part of this specification.

My invention relates to a coupler release rigging and more particularly to improvements in that form of release rigging shown and described in Patent No. 1,387,683, granted to me August 16, 1921, and comprising a connector formed of two parts hinged or pivoted together to move in a vertical longitudinal plane to compensate for the longitudinal movement of the coupler.

The object of the present invention is to so construct the device that the lower part of the connector will be supported at both ends by the upper part thus distributing the lifting power at both sides of the line connecting the locking pin and operating arm.

In the accompanying drawings which illustrate some forms of release rigging made in accordance with my invention, Figure 1 is a top plan view; Figure 2 is a side elevation, the operating arm being shown in lowered position in dotted lines; Figure 3 is a front view; Figures 4 and 5 are front and side views respectively, showing a slight modification; Figure 6 is a front view showing a further modification, and Figures 7 and 8 are front and side views respectively, showing a still further modification.

In the drawings 10 indicates the end of a railway car to which the usual rock shaft 11 is secured by brackets 12. One end of the shaft 11 is provided with a handle 13 and the other with an operating arm 14 in which is formed a horizontal eye 15. The coupler head 16 is provided with a locking pin 17, in which is formed an eye 18. All of the above mentioned parts are old and well known and form no part of my invention except in combination with the connector hereinafter described.

As in my prior patent, above referred to, the connector comprises two parts pivoted together, one engaging with the eye in the operating arm, and the other with

the locking-pin eye. In the present construction, however, instead of pivoting only one end of the upper part of the connector to one end of the lower part, I pivot both ends of the upper part to the corresponding ends of the lower part. In this manner I not only minimize the tendency to lateral pull when the draw head is moved side-wise, but also produce a much stronger link or connector in proportion to the amount of metal used.

Referring first to Figures 1, 2 and 3, the upper part of the connector consists of a U-shaped member 20 adapted to be threaded through the eye 15. One end of the member 20 is provided with a pivot opening 21 and the other is bent outwardly to form a trunnion 22. This trunnion 22 is threaded to receive a nut 23 and is either split so that it may be spread, as shown in Figure 3, or other means provided for locking the nut 23 in position. The lower part of the connector consists of an elongated loop 24 adapted to be threaded through the eye 18. One end of the loop 24 is first bent inwardly as indicated at 25, and then bent outwardly to form a trunnion 26 to engage the pivot opening 21. The other end of the loop 24 is provided with a pivot opening 27 to receive the trunnion 22 on the member 20.

In Figures 4 and 5, I have shown a slight modification in which the member 20 is replaced by a member 20^A which differs from the member 20 only in the greater width between its arms. The member 20^A is pivoted to a member 24^A differing from the member 24 in omitting the inward bend 25.

In Figure 6 I have shown a further modification in which the eye 15 is engaged by a member 20^B, which differs from the member 20^A only in being V-shaped in place of U-shaped. This member 20^B is pivoted to a member 24^A, like that shown in Figures 4 and 5.

In Figures 7 and 8 I have shown a still further modification in which the member 20 provided with hooks 28 which are open, as shown in dotted lines in Figure 8, before the parts are assembled but are bent into closed position, as shown in full lines, after the parts are assembled. In this construction the lower part of the connector consists of an elongated loop 24^B, both ends of which are bent inwardly and provided

with eyes 29 for engaging with the hooks 28. It is to be noted that the eyes 29 should be sufficiently narrow to allow of their passing through the locking pin eye 18. the other with the coupler lock-pin, both ends of said latter named part being pivoted to the corresponding ends of said first named part.

5. In all the forms above described the operation of the device will be similar to that of the structure in my prior patent above referred to except that the lifting pull will be distributed at both sides of the connector.

Having fully described my invention, I claim as new and desire to secure by Letters Patent of the United States is:

1. In a device of the class described, the combination with a coupler lock-pin, of an actuating arm therefor, and a connector comprising two parts, each provided at one end with a pivot opening and at the other end with a trunnion, said parts being pivoted together by said openings and trunnions.

4. In a device of the class described, the combination with a coupler lock-pin, of an actuating arm therefor, and a connector comprising two parts, each provided at one end with a pivot opening and at the other end with a trunnion, said parts being pivoted together by said openings and trunnions.

5. In a device of the class described, the combination with a coupler lock-pin, of an actuating arm therefor, and a connector comprising two parts, each provided at one end with a pivot opening and at the other end with a trunnion, said trunnion and opening cooperating to pivot said parts together, and retaining means engaging one of said trunnions.

55 6. In a device of the class described, the combination with a coupler lock-pin, of an actuating arm therefor, and a connector comprising two parts, each provided at one end with a pivot opening and at the other end with a trunnion, said trunnion and opening cooperating to pivot said parts together, and retaining means engaging one of said trunnions.

2. In a device of the class described, the combination with a coupler lock-pin, of an actuating arm therefor, and a connector mounted operating arm therefor, and a pair of stirrups hingedly connected at their bifurcated ends at a point between the pin and arm to move in a vertical longitudinal plane for manipulating the coupler lock.

60 6. In a device of the class described, the combination with a coupler lock-pin, of an actuating arm therefor, and a connector comprising two parts, each provided at one end with a pivot opening and at the other end with a trunnion, one of said trunnions being threaded, and a nut engaging said threaded trunnion to hold said parts in pivotal relation.

30 3. In a device of the class described, the combination with a coupler lock-pin, of an actuating arm therefor, and a connector comprising two parts, one part of said connector engaging with the actuating arm and

In testimony whereof, I have hereunto set my hand and affixed my seal.

STERLING H. CAMPBELL.
